UNITED STATES PATENT OFFICE.

IRA C. BUCKMINSTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

COATING APPARATUS.

1,407,729.

Specification of Letters Patent. Patented Feb. 28, 1922.

Application filed December 21, 1918. Serial No. 267,805.

To all whom it may concern:

Be it known that I, IRA C. BUCKMINSTER, a citizen of the United States, residing at Beverly, in the county of Essex and State 5 of Massachusetts, have invented certain Improvements in Coating Apparatus, of which the following description, in connection with the accompanying drawings, is a specification, like reference characters on the drawings indicating like parts in the several 10 figures.

My invention relates to apparatus for applying a coating fluid, as cement, to various objects, of which shoes furnish an example. 15 In such work, especially in connection with tennis shoes, it may be desired to coat the lower edge of the upper to attach the foxing, or to thus treat the bottom of the innersole and the adjacent portion of the fox- 20 ing for laying the outersole. In the first-mentioned operation especially, it is important that the upper edge of the coated surface be uniform and symmetrically located with relation to the bottom of the 25 shoe. It is the purpose of the present invention to furnish means for obtaining this result.

A feature of the invention consists in a receptacle for a coating fluid and means movable relatively thereto to remove fluid above a predetermined level, and with such an organization the work, if dipped a definite distance into the fluid, will be coated to a uniform height. Preferably the level-deter- 30 mining means operates intermittently, as between successive dipping operations, and may consist of a bar or other member movable across the top of the receptacle. This serves to level the fluid, which if it be cement 35 or other viscous substance may rise consider- 40 ably above the top of the receptacle, to the desired determined depth therein.

The distance to which the work is dipped into the coating fluid is limited by a support in the receptacle, and, to alter the relation of the upper line of the coating to the work, as a further feature of the invention I prefer to adjust different portions of the support independently, thereby rendering 45 possible a change in the angular relation of the upper line of the coating to the work. This is of especial utility in adapting the apparatus for coating different types of 50 shoes.

55 Another feature of the invention has to

do with conveying means, receiving coating fluid from a suitable source and delivering it to the applying receptacle, this conveying means having a plurality of outlets provided with controlling means, one, in the present 60 instance, being opened while the other is closed. This arrangement permits the conveying means to operate continuously. The control of the outlets is herein shown as effected by power mechanism and preferably 65 through the action of the depth-determining means. Upon actuation of the outlet closures the controlling means may be locked temporarily to allow a flow of fluid through the outlet leading to the receptacle to fill 70 this. The fluid-conveying means is further controlled incidentally to an act performed upon the work. This control, in the present instance, consists in the release of the lock for the outlet closures by contact with the 75 work as it is presented to a cleaning member.

Other features of the invention will hereinafter appear, reference being had to the accompanying drawings, in which

Fig. 1 is a top plan view of a particular 80 embodiment of the invention.

Fig. 2 is a side elevation thereof, looking from the bottom of Fig. 1, parts being broken away;

Fig. 3 is a vertical transverse section on the 85 line 3—3 of Fig. 1; and

Figs. 4 and 5 are central vertical sections through the applying receptacle, these illustrating the application of the coating fluid to the heel and ball portions and to the toe 90 portion of a shoe, respectively.

At 10 appears a tank or container serving as a source of supply for cement or other coating fluid. At one end of this tank is a well 12, the contents of which may be 95 withdrawn for cleaning through an opening normally closed by a plug 14. At one side of the well the tank has a laterally projecting portion 16 provided with a bottom wall 18 inclined from the outer end of this lateral 100 portion toward the well to permit cement falling upon the incline to return to the well. Supported near the top of the tank portion 16 by lugs 20 is a pan or applying receptacle 22; the upper edges 24 of 105 which lie in a common horizontal plane. Receiving fluid from the well is a conveyor consisting of a vertical screw 26 rotatable in a cylindrical casing 28. The lower end of this casing extends into proximity with the 110

bottom of the well beneath the cement therein, while the upper end terminates in a head 30 having spouts 32 and 34, the first delivering to the pan 22 and the second to the well. At the top of the screw is a spindle projecting through the casing head, upon which spindle is secured a pulley 36 to which power may be applied to actuate the conveyor by a belt 38 passing over guide pulleys 40 and about a pulley or belt surface 42 rotatable upon a shaft 44 journaled near the bottom of the apparatus. The pulley 42 is integral with or carried by a pulley 46 belted to a suitable source of power, this last-mentioned pulley being joined to the shaft 44 when desired by a single-revolution clutch of any convenient type controlled by a lever 48.

To support the work in predetermined relation to the edges 24, there is located within the applying pan a table 50 to the under side of which standards 52, 52, are pivoted at 54. These standards pass through and closely fit openings 50 in bosses near the opposite ends of the bottom of the pan and are threaded through spiral gears 56 held against downward movement by brackets 58 carried by the pan. With these gears 56 mesh like gears 60 upon shafts 62 journaled beneath the pan. By applying a wrench to the squared ends 64 of the shafts 62 the standards 52, and therefore the corresponding ends of the table, may be independently raised or lowered and the distance between the table and the top of the receptacle altered.

To determine the fluid level in the pan 22 by removing any excess which may rise above the edges 24, a member 66 is provided, this being shown in the form of a bar extending transversely of the pan and mounted to slide on the opposite side edges. The bar has cylindrical end portions 68, 68, each entering a slot 70 in the upper extremity of a lever 72 fulcrumed at 74 near the bottom of a casing 76 integral with or attached to the tank. To draw the bar 66 into contact with the top of the pan, tension springs 78, 78 extend from the ends 68 of the bar 66 along the levers 72 and are connected to the latter by a rod 80 which passes through openings in the levers. To the center of this rod 80 is articulated a connecting rod 82 joined to a crank 84 upon the shaft 44. When the pulley 46 is clutched to the shaft 44, as a result of the operation of the lever 48, the crank oscillates the levers 72 so that the bar 66 travels from the end of the pan adjacent to the conveyor to the opposite extremity, striking off any cement which rises above the edges 24. The forward edge of the bar is preferably provided with oppositely inclined faces 85, 85 diverging from its center, which tend to throw the fluid to the

sides of the pan rather than to force it before the bar.

The outlet openings of the spouts 32, 34 are controlled respectively by valves 86 and 88 which may be pivoted upon brackets 90 projecting from the head 30. Normally, the valve 86 is open and the valve 88 is closed, the conveyor thus delivering the coating fluid from the well to the pan. To change these valves so that the supply is cut off from the pan and the flow diverted back to the well, their position is controlled by the level-determining bar. For this purpose the valves 86 and 88 are respectively joined by links 92 and 94 to a bell-crank lever 96 fulcrumed on a bracket 98 carried by the spout 32. From the lever 96 a rod 100 extends into proximity with the opposite extremity of the tank, where it slides through a guide 102. Near the guide the bar 100 has a downward projection 104 with which the bar 66 contacts near the end of its leveling movement. This shifts the rod 100 to the left as viewed in Fig. 2, swinging the lever 96 about its fulcrum to close the valve 86 and open the valve 88. The parts are temporarily locked in this relation against the tension of a spring 106, by a latch 108 fixed upon a shaft 110 journaled across the top of the tank and engaging a depression 112 at the upper side of the rod 100.

The valves are further controlled to allow the spring 106 to return them, by contact of the work incidentally to an act performed upon it by the operator. At the end of the tank opposite the well is journaled a horizontal roll 114, the periphery of which is in proximity to the end of the applying pan. This roll is constantly rotated by a pulley 116, over which a belt 118 passes to a pulley or belt surface 120 rotatable with the driving pulley 46. Near the center of the roll 114 is a circumferential depression or groove 122, and in this groove with its side projecting beyond the periphery of the roll is a contact finger 124 secured on the shaft 110.

The finger is yieldably held with its edge outside the groove and the latch 108 pressed against the top of the rod 100 to enter the depression 112, by a spiral spring 126 surrounding the shaft and connected to it and the shaft bearing. The surface of the roll is utilized in its rotation to remove any excess of cement which there may be upon the work after it has been dipped in the pan, by presenting the surface to be cleaned to the roll, and, when this is done, the finger 124 is forced down into the roll-groove, lifting the latch from the depression in the rod 100 and permitting the spring 106 to restore the outlet valves to their normal position. To clear the roll of accumulated coating fluid, there is mounted upon a yoke

128, extending across the top of the tank beneath the roll, a scraper having sections 130, 130 contacting with the cleaning surface and a narrow central section entering 5 the groove 122.

Assuming that the apparatus is to be employed for cementing shoes for foxings or outersoles, the well portion 12 of the tank is supplied with cement, and, power being applied to the apparatus through the pulley 10 46, the conveyor screw 26 continuously raises cement from the well and in the normal position of the outlet valves delivers it to the pan. For each shoe to be cemented the operator 15 actuates the lever 48, tripping the clutch controiled thereby, which causes the bar 66 to travel the full length of the pan 22, striking off the cement rising above the edges 24. When the bar reaches the opposite end of 20 the pan from the conveyor, it contacts with the projection of the rod 100, shifting this, and therefore the valves, to shut off the supply of cement from the pan by the closure of the valve 86 and turn it back to the well 25 through the opening of the valve 88. The operator now places the shoe on the table 50, as illustrated in Fig. 4 of the drawings, with the heel and ball portion of the shoe bottom resting upon it. This causes the cement 30 to rise upon the shoe to a line determined by the adjustment of the table relatively to the edges 24 of the pan. The table height may be varied, not only to change the position of the upper line of the cemented 35 surface but also its angle longitudinally of the shoe. Then moving the shoe to the left, as seen in Fig. 5, the operator rocks it upon the ball portion to lower the toe into the cement, thus completing the coating to a uniform extent along the entire edge of the 40 upper. As the movement to the left continues, the bottom of the shoe is brought into contact with the roll 114 and any excess of cement thereon is wiped off. At the 45 same time, by contact of the work with the finger 124, the latch 108 is raised and the rod 100 released, restoring the outlet valves to their initial position. This results in the 50 pan being refilled for another operation.

Having described my invention, what I claim as new and desire to secure by Letters Patent of the United States is:

1. In a coating apparatus, a receptacle for coating fluid, and means movable relatively 55 to the receptacle to remove fluid therefrom above a predetermined level.

2. In a coating apparatus, a receptacle for coating fluid, and means intermittently operable to determine the depth of fluid in the 60 receptacle.

3. In a coating apparatus, a receptacle for coating fluid, and means movable across the receptacle to determine the fluid level.

4. In a coating apparatus, a receptacle for 65 coating fluid, and movable means arranged

to remove from the receptacle fluid rising above its top.

5. In a coating apparatus, a receptacle for coating fluid, and a fluid-leveling member movable upon the top of the receptacle. 70

6. In a coating apparatus, a receptacle for coating fluid, a fluid-leveling member movable upon the top of the receptacle, and means for intermittently moving the member. 75

7. In a coating apparatus, a receptacle for coating fluid, a fluid-leveling bar movable upon the top of the receptacle, and driving means yieldably maintaining the bar in contact with the receptacle. 80

8. In a coating apparatus, a receptacle for coating fluid, a fluid-leveling bar movable upon the top of the receptacle, an actuating lever having slotted connection with the bar, and a spring connecting the bar and lever. 85

9. In apparatus for coating the bottoms of shoes, a receptacle for the coating fluid, a support beneath the surface of the fluid upon which a shoe may rest, and means arranged to vary independently the height of the opposite ends of the support to determine the angular relation of the upper line of the coating to the shoe upper. 90

10. In a coating apparatus, a receptacle for coating fluid, means to remove fluid 95 therefrom above a predetermined level, a work-support in the receptacle, and means arranged to vary the relation of the support to said predetermined level.

11. In a coating apparatus, a receptacle 100 for coating fluid, a fluid-leveling member movable upon the top of the receptacle, a work-support in the receptacle, and means arranged to adjust the work support toward and from the leveling member. 105

12. In a coating apparatus, a receptacle for coating fluid, a fluid-leveling member movable upon the top of the receptacle, a work-support in the receptacle, and means operating independently upon different portions of the support to move said portions toward and from the leveling member. 110

13. In a coating apparatus, a source of coating fluid, a fluid receptacle in which the coating is effected, fluid-conveying means arranged to receive fluid from the source and having outlets to the receptacle and to said source, and means for controlling said outlets. 115

14. In a coating apparatus, a source of 120 coating fluid, a fluid receptacle in which the coating is effected, fluid-conveying means arranged to receive fluid from the source and having outlets to the receptacle and to said source, and means common to both outlets 125 opening one and closing the other.

15. In a coating apparatus, a source of coating fluid, a fluid receptacle in which the coating is effected, fluid-conveying means arranged to receive fluid from the source and 130

having outlets to the receptacle and to said source, and power-operated means for controlling said outlets.

16. In a coating apparatus, a source of 5 coating fluid, a fluid receptacle in which the coating is effected, fluid-conveying means arranged to deliver fluid from the source to the receptacle, and means for determining the depth of fluid in the receptacle, said 10 depth-determining means being arranged to control the fluid-delivering means.

17. In a coating apparatus, a source of 15 coating fluid, a fluid receptacle in which the coating is effected, fluid-conveying means arranged to deliver fluid from the source to the receptacle, means to determine the fluid level in the receptacle, and connections between the fluid-delivering means and the level-determining means.

20 18. In a coating apparatus, a source of 25 coating fluid, a fluid receptacle in which the coating is effected, fluid-conveying means arranged to receive fluid from the source and having outlets to the receptacle and to said source, a closure for each outlet, and connections between the closures to cause them to move together.

19. In a coating apparatus, a source of 30 coating fluid, a fluid receptacle in which the coating is effected, fluid-conveying means arranged to receive fluid from the source and having an outlet to the receptacle, a closure for the outlet, a bar movable across the receptacle, and a member actuated by the bar 35 and being connected to the closure.

20. In a coating apparatus, a source of 40 coating fluid, a fluid receptacle in which the coating is effected, fluid-conveying means arranged to receive fluid from the source and having an outlet to the receptacle, means for controlling said outlet, and means for temporarily locking the controlling means.

21. In a coating apparatus, a source of 45 coating fluid, a fluid receptacle in which the coating is effected, fluid-conveying means arranged to receive fluid from the source and having an outlet to the receptacle, means for controlling said outlet, and means for temporarily locking the controlling means, 50 said locking means being arranged for release by contact of the work.

22. In a coating apparatus, a source of 55 coating fluid, a fluid receptacle in which the coating is effected, fluid-conveying means arranged to deliver fluid from the source to the receptacle, and means operating incidentally to an act performed upon the work for controlling the fluid-delivering means.

23. In a coating apparatus, a source of 60 coating fluid, a fluid receptacle in which the coating is effected, fluid-conveying means arranged to deliver fluid from the source to the receptacle, means for determining the depth of fluid in the receptacle, said depth- 65 determining means being arranged to con-

trol the fluid-delivering means, and means under the influence of the work for also controlling the fluid-delivering means.

24. In a coating apparatus, a source of 70 coating fluid, a fluid receptacle in which the coating is effected, fluid-conveying means arranged to receive fluid from the source and having outlets to the receptacle and to said source, a closure for each outlet, a bar movable across the receptacle, a member actuated by the bar and being connected to the closures, means for locking the actuating member with the closures in one position, and means for releasing the locking means to permit the closures to assume another position.

25. In a coating apparatus, a source of 85 coating fluid, a fluid receptacle in which the coating is effected, fluid-conveying means arranged to receive fluid from the source and having outlets to the receptacle and to said source, a closure for each outlet, a bar movable across the receptacle, a member actuated by the bar and being connected to the closures, means for locking the actuating 90 member with the closures in one position, and means under the influence of the work for releasing the locking means.

26. In a coating apparatus, means for 95 applying a coating fluid to the work, means for delivering the coating fluid to the applying means, a work-cleaning member situated adjacent to the applying means, a member for contact with the work while it is being acted upon by the cleaning member, and connections between said contact member and the fluid-delivering means.

27. In a coating apparatus, means for applying a coating fluid to the work, means for delivering the coating fluid to the applying 105 means, a grooved roll rotatable adjacent the receptacle, a movable member projecting from the groove, and connections between said member and the fluid-delivering means.

28. In a coating apparatus, means for applying a coating fluid to the work, means for delivering the coating fluid to the applying 110 means including a fluid-controlling valve, means for moving the valve, means for locking the valve in the position to which it is 115 moved, and releasing means for the locking means acting under the influence of the work.

29. In a coating apparatus, a tank for 120 coating fluid, an applying receptacle situated therein, a conveyor receiving fluid from the tank and having outlets to the tank and receptacle, and means for removing an excess of fluid from the receptacle for return to the tank.

30. In a coating apparatus, a tank for 125 coating fluid, an applying receptacle situated therein, a conveyor receiving fluid from the tank and having outlets to the tank and receptacle, means for removing an excess of 130

fluid from the receptacle for return to the tank, valves controlling the conveyor outlets, and means operable by the removing means for controlling the valves.

- 5 31. In a coating apparatus, a tank for coating fluid, an applying receptacle situated therein, a conveyor receiving fluid from the tank and having outlets to the tank and receptacle, means for removing an excess of 10 fluid from the receptacle for return to the tank, valves controlling the conveyor outlets, means operable by the removing means for controlling the valves, a lock for the controlling means, a work-cleaning member, 15 and means associated with the work-cleaning member for releasing the lock.
32. In an apparatus for coating the bottoms of shoes, a receptacle for the coating

fluid, a support beneath the surface of the fluid upon which a shoe may rest, and means 20 extending beneath the shoe-support and including a portion at one side of the receptacle arranged to vary the height of the support to determine the line of application of the fluid.

25 33. In a coating apparatus, a source of coating fluid, a fluid receptacle in which the coating is effected, fluid-conveying means arranged to deliver fluid from the source to the receptacle, and means constructed and 30 arranged for operation by the work for controlling the fluid-delivering means.

In testimony whereof I have signed my name to this specification.

IRVING C. BUCKMINSTER.

Certificate of Correction.

It is hereby certified that in Letters Patent No. 1,407,729, granted February 28, 1922, upon the application of Ira C. Buckminster, of Beverly, Massachusetts, for an improvement in "Coating Apparatus," errors appear in the printed specification requiring correction as follows: Page 1, line 72, for the misspelled word "per- fomed" read *performed*; page 2, line 60, after the syllable "tremity" insert the words *and returns*, and lines 61 and 62, for the words "The forward edge of the bar is" read *The edges of the bar are*; page 3, line 17, after the reference numeral "22" insert the words *and back to its normal position*; page 4, line 56, claim 22, strike out the word "operating" and insert *constructed and arranged for operation*; and that the said Letters Patent should be read with these corrections therein that the same may conform to the record of the case in the Patent Office.

Signed and sealed this 12th day of September, A. D., 1922.

[SEAL.]

KARL FENNING,

Acting Commissioner of Patents.
